To all whom it may concern:

Be it known that I, Stephen D. Arnold of New Britain County of Hartford and State of Connecticut, have invented or discovered a new and original design for Lifting Handle plate; and I do hereby declare that the following is a full and exact description of the same, reference being had to the accompanying photographic views, in which the same letters indicate like parts.

In the accompanying illustrations are shown a new and original design for a lifting handle plate, foliated with strawberry vine, leaf, and fruit surrounding a disk configuration a, with raised rock-ers c. The whole combined to produce a rich and ornamental plate.

What I claim therefore and desire to secure by Letters Patent, is the above described ornamental design cast or struck up for a lifting handle plate substantially as set forth.

Witnesses,

Chas Peck,
Birdseye Beekley,

Stephen D. Arnold (seal)
